COIN SINGLING AND SORTING DEVICE

Fount F. Daugherty, St. Louis, Mo., assignor to Thomas Francis, Fount F. Daugherty, Neal S. Wood, Thomas H. Mize, Idus L. Rhodes, W. J. Moran, Laura P. Carpenter, David R. Francis, all of St. Louis, Mo., and Nathaniel Ewing, Fort Lewis, Wash., as trustees

Original application January 2, 1940, Serial No. 312,012. Divided and this application November 17, 1943, Serial No. 510,834

13 Claims. (Cl. 194—6)

1

This invention relates to improvements in coin handling devices, and more particularly to an improved coin singling and sorting device adapted for embodiment in a fare box for use on street railways, buses and the like. The present application is a division of my copending application for Coin Handling and Totaling Devices, filed January 2, 1940, and bearing Serial No. 312,012, and now issued as Patent No. 2,338,575, dated January 4, 1944.

A general object of the invention is to produce an improved coin singling and sorting mechanism susceptible of a variety of uses other than in connection with a fare box assembly as herein broadly exemplified, being the fare box fully and completely shown and described in the parent application hereinabove referred to, and further to provide in one preferred embodiment of the mechanism, as will hereinafter appear, for operator-observation of coins passing through the sorting mechanism and for operator-access to the coins therein so as to facilitate detection and removal of spurious coins inadvertently or otherwise admitted to the fare box.

Another object of the invention consists in the provision of improved power-driven mechanism for the purposes of singling and sorting coins received in the payment of fares or the like. In connection with the improved power-driven mechanism for the purposes above indicated, the present invention contemplates in one embodiment thereof, control means serving to initiate operation of the power-driven mechanism in response to the introduction of a coin to the coin-singling zone of the machine.

The foregoing objects and many others will clearly appear as the description proceeds, and as considered in view of the accompanying drawings forming a part of this specification, and in which:

Fig. 1 is a vertical elevation in perspective, of the fare box assembly embodying features of the present invention;

Fig. 2 is a vertical sectional elevation on a somewhat larger scale than Fig. 1, of the upper or coin receiving section of the fare box assembly, as viewed along line 2—2 of Fig. 3;

Fig. 3 is a horizontal section in plan, of the coin receiving section of the box, as viewed from line 3—3 of Fig. 2;

Fig. 4 is a fragmentary vertical section in a plane transverse to that of Fig. 2, and as viewed along line 4—4 of Fig. 2;

Fig. 5 is a vertical elevational view of the fare box, a portion thereof being broken away to illus-

2

trate partly in elevation and partly in section, elements of the mechanism embodying features of the present invention;

Fig. 6 is a horizontal section through the fare box, as viewed from the stepped line 6—6 in Fig. 5;

Fig. 7 is a vertical side elevation of the box assembly, shown partly in section as viewed from the line 7—7 in Fig. 6;

Fig. 8 is a fragmentary vertical section as viewed from line 8—8 in Fig. 7, illustrating certain features of the coin singling and sorting mechanism;

Fig. 9 is a fragmentary plan view, partly in section, of the coin singling device and coin gauge, the view being taken from line 9—9 in Fig. 5;

Fig. 10 is a fragmentary, horizontal section through an upper portion of the box, illustrating a modified form of coin singling and sorting mechanism;

Fig. 11 is a fragmentary vertical sectional elevation, as taken along line 11—11 of Fig. 10;

Fig. 12 is a fragmentary vertical elevational section, taken in a plane transverse to that of Fig. 11, and showing details of the modified coin sorting mechanism;

Fig. 13 is a fragmentary section transversely through the modified coin singling device of Fig. 10, as viewed along line 13—13 thereof;

Fig. 14 is a similar fragmentary section as taken along line 14—14 of Fig. 10;

Fig. 15 is a detail elevation of a cam drive for a coin control device shown in Fig. 11, the view being taken from line 15—15 of Fig. 11, and

Fig. 16 is a detail elevation of a coin sorting control device forming a part of the modification.

In the present description, in order to facilitate cross-reference between the present and parent applications, the same reference characters have been employed, insofar as applicable to both descriptions.

By way of general preliminary reference to the assembly as a whole, it is preferred to enclose the parts in a housing indicated generally at 30, and characterized by a front wall 31, so called since it is usually located closest to and facing the operator, side walls 32 and 33 respectively, and a rear wall 34. The housing is conveniently formed of sheet metal of substantial gauge, and is surmounted by a frusto-pyramidal portion 35, serving in turn to carry a cylindrical coin receiver 36. The latter is desirably formed of a heavy glass and is positioned by hooks 40 extended through the housing portion 35 and secured in

place by suitable nuts 41. Within the receiver is a coin chute structure 42 characterized by an improved arrangement of its elements to prevent manual access to the interior of the receiver. The chute structure includes an inverted frustoconical pan 43 projecting downwardly in the coin receiver 36 and provided with an opening 44 in the lower end thereof. The upper end of the pan preferably terminates in an annular flange 45 which is provided with an annular recess 46 in the under surface thereof, to receive the upper margin of the cylinder 36, the flange being held beneath the hooks 40 as shown in Fig. 2. Vertically slideable on headed screws or bolts 47 secured to and depending from the lower end of the pan 43, is a relatively flattened conical member 48 which in its normal position as shown, clears the pan opening 44 sufficiently to allow coins, tokens or the like, to pass therethrough and downwardly in the coin receiver, over the member 48. If for any reason, the fare box assembly is wholly or partly inverted, as in an attempt to remove coins from the receiver 36, the conical member 48 under the action of gravity thereon, will slide toward the pan 43 with its apex portion entering the pan opening day 44, thereby effectively closing the opening against outward passage of such coins as may be in the receiver.

A further provision is made in the chute structure, to foil attempts at removal of coins from the receiver while the fare box is in its normal, upright position. Such means comprises a plurality of hinged elements or flaps 49 which normally depend vertically from the periphery of the conical member 48, and are prevented from swinging inward by inwardly directed fingers 50 on the several elements, which abut the under-surface of the member. The lower end of each element is notched or serrated, as shown at 51. Thus in the event coin removal is attempted by the use of gum or other adhesive substance on the end of a cord or the like, retraction of the coin will be effectively arrested by contact of the coin with one or more of the flaps 49, the latter thereby being swung outwardly and upwardly, to span the space between the member 48 and the glass cylinder 36. The notches in the flaps, of course, serve to catch and receive the cord in one thereof, so that in the attempt to remove a coin, such coin will be directed toward and into a position underlying the flap engaged by the cord.

In the lower portion of the receiver cylinder 36 is a pan 52, the bottom wall 53 of which is sloped to direct the coins toward an open neck 54 thereof. Surrounding and substantially subtending the neck 54 is a camming ring or wiper 55, serving as a continuation of the neck to direct the coins from the pan to the singling plate, later to be described. The annular wiper 55 is best seen in detail in Fig. 4, the annulus being provided with an extension 56 pivoted as by pin 60 engaging a projection 61 on the pan 52. The projection 56 extends beyond the pin 60 to form an arm for receiving a spring 62 anchored also to the pan 52 in a manner to urge the opposite side of the camming ring downwardly, somewhat away from the pan 52, and against a singling disc or coin carrier, to be described. In order to aid in directing a coin received by the pan and ring 55, to a flat position on the singling disc, I prefer to form the ring 55 with one or more projections 63 on its inner surface, such a projection or projections being formed thereon in the zone of a downwardly extending lip 65, the

lower margin of which bears against the upper surface of a singling disc 70, later to be described in detail.

As appears in Figs. 2 and 3, the bottom wall 53 of pan 52 is provided with a multiplicity of openings 66 therein, which allow dirt and particles of foreign matter entering the coin receiver 36, to drop therethrough onto a dirt-collecting plate 67 located therebelow. The plate 67 is provided with a circular flanged opening 68 to receive the lower end of the camming ring 55.

Coin singling and sorting mechanism

The disc 70 is constructed to rotate in a horizontal plane beneath the plate 67, and overlies a stationary bed plate 71, forming an upper journal 72 for a vertical drive shaft 73, the shaft being secured axially to the disc or plate 70. The disc 70, as best appears from Fig. 9, is provided with a pair of diametrically opposed coin-receiving apertures 74 and 75, these apertures being bevelled inwardly from their upper surface as shown at 78, the bevelled edges tapering inwardly to a thickness of approximately thirty thousandths inch, being about the gauge of a worn ten-cent piece. This precludes, as will appear, the carrying of more than one coin, even though it be of minimum thickness. The arrangement is such that as the coin is deposited in the top of chute 42 and falls into pan 52, it is directed into the ring 55 and falls onto projection 63. It is caused thereby to lie flat in a horizontal plane in the bottom of that one of the disc openings or apertures 74 and 75 which is next brought under and in register with the ring 55. Since the plate 71, except for its coin discharge aperture 77 (Fig. 8), constitutes a bottom for each of the coin-receiving recesses of the disc 70, the coin will be moved in a horizontal plane until it falls or is ejected, as later described, from its position in the singling disc 70. The projection 63 and lip 65 have been so designed and located as a result of numerous experiments, and so coated as practically to assure the deposit of the coin in flat horizontal position in the singling disc. Since the coin is impelled in the disc only by abutment of one of the thin arcuate edges 78 with the edge of the coin, any more than one such coin, even though it be a thin ten cent piece, will be wiped out of the coin seat 74 or 75 by the lip 65 of the spring loaded wiper ring. In this manner the disc and ring coated to prevent the movement of more than one coin at a time, to the position of discharge.

Discussing briefly now the manner of driving the shaft 73, and referring particularly to Figs. 5 and 6, I prefer to utilize an electric motor 79 arranged in the lower portion of the fare box 30, and the operation of which is controlled by a suitable line switch 80 (Fig. 1) having its switch-actuating element 81 accessible from the exterior of the fare box, as shown. The motor is operatively connected to a reduction gear assembly (not shown), housed in a gear box 83, the latter in turn being suitably drivingly connected to the lower end of a shaft 86 which extends vertically above the gear housing (Fig. 5), the lower end of the shaft 86 being suitably journaled (not shown) within the gear box. The upper end 88 (Fig. 6) of the shaft 86 is suitably journaled (not shown) in a horizontal plate 89 (Fig. 5) forming a part of the fare box frame, and projects thereabove to provide for connection of a drive pinion 90 thereto, as shown in Fig. 6. This element enmeshes with a relatively

large diameter gear wheel 91 operatively secured to the lower end 92 of the shaft 73, to effect the drive therefor. As appears in Fig. 5, the shaft 73 at its lower end 92, is journalled in the frame plate 89 at 93.

Referring further to the action of the coin as it is brought into one of the recesses in the singling disc 70, the projection 63 internally of the ring 55 and in the zone of the downwardly projecting lip 65 thereof, has the effect of camming the coin downwardly into a horizontal position, in case it has not originally assumed such a position. The coin, having been deposited in one of the singling disc openings, say 74 (Figs. 2, 3 and 9), when such opening registers with the ring 55 (the position of ring 55 relative to the disc 70 in plan elevation, being shown in Fig. 9, by the broken line circle there designated by the numeral 55), will be carried by rotation of disc 70, to the position occupied by the opening or recess 75 as shown in Fig. 9, at which position is located a coin-gauge presently to be described. Beyond the latter position, the coin will engage a bow spring 100 appearing in Fig. 5 and also shown in broken lines in Fig. 8, the coin having been moved in the direction shown by the arrow (Fig. 9) to the position of the discharge port 77. As best appears from Fig. 8, the bow spring is carried by the upper deck plate 67 in a position to overlie the discharge port 77, such that the coin, in engaging the same, is turned edgewise into a chute therefor, hereinafter described. In Fig. 9, the location of the discharge port 77 relative to the disc 70 and to the coin-gauge shown at 103 and hereinafter described, is clearly shown by the broken-line circle at the lower end of the figure, designated by the numeral 77. During its displacement by the disc 70, the coin or token (the terms herein being employed interchangeably) will engage on its periphery, a non-yieldable stop 101 (Fig. 9) carried by and projecting upwardly from the plate 71. The opposite peripheral portion of the coin 102 will be brought to bear against a movable gauge element 103 which is displaced a greater or less distance outwardly of the axis of the disc, according to the diameter of the coin. According to the present exemplary disclosure and as best appears from Figs. 5, 8 and 9, the rotary disc 70 is annularly undercut as at 98, in order that the disc may clear the gauge element 103 and so that an edge of a coin may engage the element 103 to actuate the same for a purpose presently to appear. Further, the disc 70 in the hub zone thereof, is provided with arcuate slots or grooves 99 to accommodate the fixed stop 101 upstanding on plate 71 opposite the gauge 103 (Fig. 9) as the disc rotates. The position of stop 101 is such that it will be exposed for engagement by a coin in one of the openings 74 and 75 in disc 70, as one or the other of the openings approaches the zone of the stop and gauge 103, as this is illustrated clearly in Fig. 9. A vertical side elevation of the movable gauge 103 is shown by Figs. 5 and 8, and it is constrained to a straight-line lateral movement by a guide recess 104 formed in the bed plate 71 to receive the gauge. The gauge 103 is connected to a movable coin chute 105 swingably mounted about a pivot 106, the connection being made through a linkage assembly including a lever 107 pivoted intermediate its ends, about a pin 108 carried by lugs 109 formed internally of the housing 30. The upper end of the lever 107 is operatively associated

ed with the gauge 103 through the pin and slot connection 110 as shown, such that the translatory movement of the gauge will result in pivotal movement of the lever. To the lower end 111 of the lever and on one side thereof, is pivotally connected one end 112 of a link element 113, the opposite end 114 of the latter being in turn, pivotally connected as at 115, to the swingable chute 105, as best appears in Figs. 6 and 8. The foregoing pivotal connection is effective so as freely to translate the straight line movement of the gauge to an arcuate movement of the coin-chute.

The path of the chute 105 is such that its discharge or delivery end may be brought selectively into register with the receiving ends of the fixed coin chutes 120, 120A, 120B, 120C, 120D, 120E, and of a somewhat enlarged chamber or pocket 120F located externally of and immediately beyond the chute 120, and provided for receiving any object smaller in diameter than the smallest coin or token received in the fare box. The chutes number 120, 120E which are of rectangular transverse section as will appear in Figs. 6 and 8, are directed downwardly, and toward the front wall 31 of the housing 30, such that the lower open ends thereof may register with coin-receiving openings 121 in corresponding magazines 122-122E (Figs. 1, 7 and 8) of a preferably detachable money changer.

From the foregoing it will appear that the movable chute 105 is positioned by movement of the coin gauge to discharge above the fixed chute appropriate to receive such coin, the chute 120 being utilized, for example, for small tokens, 120A for dimes, 120B for pennies, 120C for large tokens, 120D for five cent pieces and 120E for quarters. The exact number of the fixed chutes and magazines will depend upon the particular requirements of service.

In the use of fare boxes in public carrier vehicles, attempts are not infrequently made by unscrupulous employees to remove coins by inversion of the box. This has been referred to hereinbefore, in connection with the adaptation of the chute structure 42 in the coin receiver 36, to prevent the removal of coins in such manner. However, an additional device for thwarting such attempts is embodied in a safety ball 123, normally retained in a pocket 124, therefor, carried by the chute 42. In case the box is tilted beyond a critical angle, the ball falls from the holder 124, and thereafter to a position in one of the recesses of the singling disc (Fig. 4), and so prevents any additional coins passing through the disc until the ball is restored to the pocket. The relative sizes of the ball and apertures 14-75, as well as aperture 125 in the bed plate 71, are such that the ball will never pass below the plane of the bed plate. The arrangement described enables the certain detection of any attempted removal of coins by inversion or tilting of the fare box.

To summarize the action of the coin singling and sorting mechanism, it will now appear, for example, that a coin of the largest contemplated diameter, say a 25¢ piece, when received in the singling element 70 and displaced thereby, will first encounter the coin gauge 103 by abutment of a bevelled or camming surface 126 thereof and will continue to displace the element 103 until it occupies the outermost limit of its movement. By reason of such extreme range of gauge movement, the delivery end of chute 105 will have moved through its greatest range, or to a position

opposite the chute 120E. After the coin has cleared the gauge and has been delivered through the chute 105, the gauge is returned to its initial position shown in Fig. 9, this return movement being effected by a spring 127 (Fig. 5) which is operatively associated with the gauge in a manner presently to be described. It is to be noted here and as clearly appears in Fig. 8, that when the gauge is disposed in its initial position, the delivery end of the coin chute 105 will be thereby positioned in register with the receiving end of the chamber or pocket 120F. Hence, upon the introduction of a coin or any other object, as a button, smaller in size or diameter than the smallest coin or token to be received and sorted by the device, such object will not displace the gauge, but will be delivered directly into the chute and thence pass into the chamber 120F, for later removal.

Action of the spring 127 for returning the gauge 103, as well as the chute 105, to initial position, is delayed for a predetermined time following coin-positionment of the gauge, so that the chute 105 may be retained in gauge-actuated position at least until the coin therein is delivered from the chute 105 into one of the underlying coin-chutes. The delay in the gauge return function of spring 127 may be effected in any desired manner, but as here preferred, it is accomplished as follows:

Referring to Fig. 5, the spring 127 is coiled about an arm 142 having pivotal connection at one end, to the gauge arm 107. One end of the spring is pinned or otherwise fixed to the arm 142, while its opposite end bears against a stationary member 143. Thus it will appear that the spring is thereby effective to urge the arm 142 and hence the lower end of lever or arm 107, toward the left as viewed in the figure, so that arm 107, being pivoted intermediate its ends, as at 108, may displace the gauge 103 to its inward or coin-engaging position, as shown in Fig. 5. Arm 142 is projected through member 143 (Figs. 5, 6 and 7) and is urged upwardly therein against a roller 145, by a spring 147. Notches or teeth 150 are provided along the lower margin of arm 142 for coaction with a pivoted, spring-loaded pawl 151 carried by member 143, the pawl being effective against the teeth 150 to retain the arm 142 in gauge-actuated position, when the arm 142 is somewhat depressed. Means for depressing the arm 142 in timed relation to the coin-affected gauge position of the arm against the return-force of spring 127, is found in a cam element 139 driven in timed relationship with singling disc shaft 73 through a vertical camshaft 136 to which the cam is fixedly secured, and cam-shaft gear 138 enmeshing pinion 90 on shaft 88. Cam 139 is adapted for engagement with the outer or free end of pivoted arm 142, through a friction-reducing roller 141 on the arm, such engagement occurring only when arm 142 is projected by gauge actuation, so as to bring its roller 141 within the path of the cam surface or camming lip 152—140 of the cam. At such time, the cam serves to depress arm 142 so as to engage the pawl 151 with the teeth 150, whereby to hold the arm 142 in its gauge-actuated position until released by further action of the cam 139, such as to permit upward, pawl-disengaging movement of the arm 142, the latter occurring when or after a coin in chute 105 has been delivered into one of the coin-chutes hereinbefore described. Cam-depression of arm 142 when in gauge-actuated position, may be utilized to effect or initiate by means of the arm, operation of other mechanism.

of the fare box assembly as fully illustrated in the application hereinbefore noted, of which this application is a division.

It will have been observed that the device according to the embodiment thus far described, is completely operative for the purpose of singling the coins, carrying them in flat singled relation, and discharging them, each into its appropriate receiver or magazine of the changer 122. The changer 122 may be of conventional form, such that the several coin magazines are each provided with a coin-receiving mouth or chute numbered 128, 128A through 128E, accessible externally of the fare box for direct insertion of coins in the money changer.

Modified coin singling and sorting device

There may be employed in a fare box of the character herein indicated, a somewhat modified coin singling and sorting mechanism, which accomplishes the same result attained by the singling and sorting device hereinbefore described, but in a different and yet improved manner. The modified device for example, enables the car-operator to follow and check or remove spurious coins during the sorting process of the machine. Additionally, provision is made therein for initiating operation of the motor 79 from which all of the operating parts of the machine are driven, solely in response to the reception of a coin in the coin-singling zone of the singling device. These and further improvements will become apparent as the description proceeds.

Referring now in particular to Figs. 10 and 11, and to Fig. 2 for reference to the coin-receiving and directing plate 52 as appears therein, the coin plate 52 in the present modification is by preference, arranged somewhat lower in the box housing, such that its coin-discharge end 54 is disposed within the frusto-pyramidal housing section 35 (Fig. 1) and adjacent one wall thereof. In register with the circular discharge aperture provided by the plate end 54 and depending therefrom, is a tubular member or coin-receiving conduit 559 (Fig. 11), the lower end 551 of which engages and rests upon a surface portion of a plate-like member 552 seated in an aperture 553 (Fig. 13) provided therefor, in a horizontal bed plate 554, the location of the member being inwardly adjacent the housing side wall 33, as appears in Fig. 10. The member 552 is formed to present opposite laterally projecting flanges 555 (Fig. 13) which seat upon the adjacent margins of the bed plate and through which the member is secured to the plate, as by screws 556 (Figs. 10, 13 and 14). Extending centrally and longitudinally inwardly from one end 557 of the member 552, is a channel 558, adapted for the reception of a coin-singling plunger or slide 559 which is retained for reciprocal movement therein, by guide flanges 560 formed on the member and closely overlying the plunger when engaged in the channel. The forward or coin-engaging end 561 of the plunger is bevelled as shown in Fig. 11, to present a coin-contacting edge 562 of a thickness corresponding to the gauge of say, a worn ten-cent piece which may be introduced to the machine. Thus the plunger is adapted for contact with but one coin at a time. The lower end portion of the tubular member 550 adjacent the plunger channel, is undercut as at 563, so that the slide may pass thereunder and over the surface portion 564 of the member 552, which underlies the tubular coin conduit 559. In order to assure the singling and discharge of but one coin at a time, from the coins collecting in the

conduit 550 and resting upon the surface 564 therebelow, the lower conduit end portion which overlies the coin discharge surface 565 of member 552 is undercut as shown in Fig. 11. Releasably closing the opening resulting from undercutting the tubular member in the zone indicated, are adjoining arcuate singling fingers 566 which are movable vertically, upon finger mounting pins or studs 567. Coiled springs 568 encircling the several pins 567, serve to urge the fingers downwardly against the surface 565 of member 552. The lower ends of the fingers are bevelled as shown, to provide camming surfaces for coaction with the bevelled forward edge of the coin plunger 559, as the plunger passes beneath the fingers in its movement to displace a coin toward sorting mechanism later to appear, thereby camming the fingers upwardly. Although cammed upwardly by the plunger, the fingers nevertheless remain in spring-urged contact with the latter, which serves effectively, to prevent plunger-ejection of more than one coin from the coins received in the conduit 550.

Actuation of the plunger 559 for reciprocating movement thereof, is effected from the motor 79 (Fig. 5), through a vertical drive shaft 569 journaled in bearing brackets 570. The shaft 569 corresponds in purpose, to the shaft 73 of the singling mechanism shown by Fig. 5, and hence, it may be driven from the motor 79 through a connection (not shown here) which may be similar to that provided for shaft 73. To the upper end of shaft 569 is operatively secured a wheel 571, the wheel having pivotally secured upon its upper surface and adjacent the periphery thereof, one end of a plunger-operating link 572, the pivotal connection being effected in the present example by a pin 573. The opposite end of link 572 is similarly pivotally connected to the rear or trailing end of the plunger, as by a pin 574. The arrangement is such that for each full revolution of the shaft and wheel 569—571, the plunger 559 will be reciprocated once, between the limits of its travel. The normal or initial position of the plunger is that shown by Fig. 10, wherein it is retracted from beneath the coin conduit 550.

Energization of the motor 79, for operation of the coin-singling and sorting mechanism, as well as other elements of the fare box, such as registering and recording mechanism (not shown), is controlled from the coin-receiving surface portion 564 of member 552, by motor-circuit controlling contacts now to be described. Embedded in the member 552 so as to be exposed centrally of the surface 564 thereof, are contact elements 575, each projecting beneath the member 552 to provide terminals 576 for connection in controlling relation to the motor power circuit (not shown). The arrangement of these contacts in the motor circuit is such that upon a coin being received in the fare box and coming to rest while flat upon the surface 564 of the singling device, the coin being metallic and further, in nearly all cases, characterized by metal of good electrical conductivity, will serve thereby to bridge the contacts and hence to complete the motor circuit therethrough. Thus, motor operation being initiated in this manner, the plunger 559 will be then displaced forwardly over the surface 564, to single and displace the lowermost coin toward and into a coin sorting device presently to appear. In order to continue the operation of the motor 79, so that it may drive the mechanism of the fare box, as the singling and sorting mechanisms, to the end of the cycle for each coin and until the

plunger is again retracted to its initial position, ready for the singling of the next coin coming into contact-bridging relation to the contacts 575, there is embedded in the under surface of the plunger 559, a contact-bridging plate 577 which is adapted and so located as to bridge the contacts before the coin providing the initial contact-bridge, is displaced therefrom. The plate 577 then serves to maintain the motor circuit closed during the singling and coin ejecting function of the plunger, and until the plunger is substantially returned to initial position. It will be observed that the circuit is opened at contacts 575, just prior to the full-return of the plunger, but the drive momentum then existing, will complete the plunger return, as will be appreciated. Also, and for reasons now readily apparent, the coin conduit 550, plunger 559, base member 552 and optionally, the singling fingers 566, are formed from suitable insulating material, as hard rubber, Bakelite, or the like.

As a coin is singled and ejected from the singling zone, by the plunger 559, it is thereby displaced over the surface 565 of member 552 and beneath a guide plate 578 overlying the surface 565 (Figs. 10, 11, and 14), toward and into a tapered, coin-receiving mouth or chute 579 of the coin sorting mechanism denoted generally, by the numeral 580 (Fig. 11). However, before the coin is discharged into the chute 579, a marginal portion of the coin contacts a roller 581 journaled on a fixed pin 582, the roller providing one element of coin-gauge mechanism now to appear. Immediately prior to or as the coin contacts the roller 581, it engages on another peripheral portion thereof, a roller 583 carried on one end of a pivoted lever 584, and located to one side of the line of coin-travel from the singling zone. The lever 584 pivoted intermediate its ends, as at 585, will be pivoted in a clockwise direction as viewed in Fig. 10, as the coin abuts the roller 583 thereon, the pivotal movement of the lever continuing until the coin attains a position diametrically between the rollers 581 and 583. The extent to which the lever is thus pivoted, to the point where the coin is located diametrically between the rollers, thus provides an index as to the diameter of the coin, and hence of its denomination. Thus the lever 584 and its roller 583 constitute a coin gauge which corresponds in purpose, to the coin gauge 103 hereinbefore described and as shown by Figs. 5 and 9. Accordingly, the lever 584 is utilized for operating elements of the coin sorting mechanism 580, as will presently appear. It is to be noted as a preference in the present example of the modified coin singling structure, that the coin gauge arm 584 and its roller 583, the roller 581 and the guide plate 578, all are formed from suitable insulating material, as hard rubber, Bakelite, or the like. Also, as shown by Fig. 14 in particular, a portion of the plate member 552 is cut-away, as at 586, to accommodate the gauge roller 583 and thereby, to facilitate presentation of the roller surface for contact by each coin ejected from the singling zone of the device.

Pivottally connected to the opposite end 587 of the gauge lever 584, is one end of a bar or lever 588, the opposite end of the latter being in turn pivottally connected to the outer or free end 589 of a crank arm 590 (Fig. 10). The hub 591 of crank 590 is operatively secured to a vertically arranged stub shaft 592, which is journaled in and extends downwardly through the bed plate 75 554. Fixedly connected to the shaft 592 but

below the plate 554 is another crank arm 593, the outer end of which is visible through the break 554a in the plate 554. A yoke 594 is connected to the outer end of arm 593 by a pin 594a and slot 594b. Arm 142a, corresponding to arm 142 of Figure 5, has a pivoted connection with the yoke 594 as by means of a pin 594c, the arm 142a being guided in a vertical plane by the side guide plates 594d or the like. The spring 127a associated with the crank arm 590 as illustrated in Figure 10, functions in the present modified mechanism as a return spring for urging the gauge lever 584 into its initial position shown in Fig. 10. Also, the desired delay in the return action of spring 127a is effected in the present embodiment, through arm 142 in the manner hereinbefore described and as illustrated by Fig. 5.

Turning now to the coin sorting mechanism 580, for the purpose of the present example, it is adapted for sorting and delivery of coins of but five different sizes, to a detachable money changer 595 (Fig. 12) having a corresponding number of coin chambers, as the chambers 595A for quarters, 595B for nickels, 595C for pennies, 595D for dimes and 595E for tokens of one given size (Fig. 12). The changer 595 here employed, may correspond in type and structure to the changer shown by Fig. 1, differentiating therefrom only in that it provides but a single token chamber instead of the two for different size tokens, in the latter changer. However, it is to be understood that the presently modified sorting mechanism may be readily adapted to the six-chambered changer 122, or to any other changer providing a desired number of coin receiving chambers.

The device 580 includes a coin-chute structure 596 of plate-like form, which is arranged in a vertical plane and located above and in vertical registry with the coin-receiving openings of the changer 595, the plate structure further extending between the opposite side walls 32 and 33 of fare box housing (Fig. 12). The structure 596 is formed to provide in an upper corner thereof, a coin-receiving throat 597 with which is registered the coin passage 598 in a member 599 providing the coin-receiving mouth 579, the latter being in line with the discharge zone of the singling mechanism, as before described. As appears in Figs. 10 and 11, the tapered mouth 579 is so adapted as to turn a coin received therein, for vertical edgewise delivery thereof downwardly in the passage 598, in which relative position the coin thence proceeds through the sorting device. The structure 596 is formed further, to provide in communication with the throat 597, a downwardly inclined coin-passage 600 which terminates at the opposite plate end 601, in a vertical coin-chute 602 extending downwardly through the lower edge 603 of the structure. The coin-receiving mouth 579, passage 598, throat 597, inclined passage 600 and chute 602 are all of a size sufficient to accommodate the largest-diameter coin handled by the machine, as a quarter, while the downward inclination of the passage 600 is such that the coins admitted to the sorting device, may gravitate downwardly therein. A series of openings 604, 605, 606, and 607 (right to left in Fig. 12) are provided in the bottom or lower margin 608 of the passage 600, through which vertical coin-chutes 609, 610, 611 and 612 respectively, communicate with the passage 600. The arrangement is such that the opening 604 and the communicating chute 609

which substantially underlie the coin throat 597, are of a size to receive tokens of a given diameter; the next adjacent opening 605 and its chute 610 of a size to receive dimes; the next opening 606 and chute 611 of a size to accommodate one-cent pieces or pennies; the next opening 607 and its chute 612 of a size to receive nickels, and the last chute 602 as before described, of a size to accommodate quarters. The lower open ends 10 of the several chutes then register with the corresponding coin chambers of the changer 595 therebelow, as the quarter chute 602 with the quarter chamber 595A, the nickel chute 612 with the nickel chamber 595B, and so on through the 16 series.

In order to direct a coin of a given size or denomination, into the particular one of the coin-chutes provided for receiving the same, a coin-chute control device 620 is associated with the 20 chute structure and is operated from and in response to operation of the coin gauge 584. For this purpose, a slot 621 is provided laterally through the chute structure 596 and along the lower margin 608 of the passage 600, through 25 which may be projected a stepped end section 622 of a control plate 623. The plate 623 suitably supported for displacement toward or away from the slot 621, has its stepped section arranged so that when the plate is moved from an initial position outwardly of the slot 621, to a predetermined position, the forwardmost step 624 will project over the opening 604 to the token chute 609, hence closing this chute to the entrance of a coin 30 therein, but permitting a coin to pass over the step and downwardly in the passage 600 to a lower chute. Further movement of the control plate to another predetermined position, will serve to bring the next adjacent step 625 over the opening 605 to coin chute 610, thus closing-off this chute as well as the first chute 609, but permitting a coin to pass through passage 600 to a lower chute. In a similar manner, further successive movements of the control plate through the slot 621, will effect through its steps 626 and 35 627, successive closures of the chute openings 606 and 607, and hence, when all of the openings 604—607 are thus closed, the only chute remaining open to receive coins will be the last or quarter chute 602.

Operation of the control plate 623 is effected from the coin gauge lever 584 through a drive now to appear. Slidably supported by a bracket 628, is a bar 629 suitably connected at one end, to the plate 623, and provided with gear teeth 629A on its opposite side portion, thus providing a gear rack. Enmeshing with the rack is a gear 630 which is journalled in brackets 631 secured to and depending from the bed plate 554. The bed plate 554 is apertured in the zone of the gear 630 as at 632, through which the gear projects so as to be exposed above the plate (Fig. 11). The location of the gear 630 is such, as appears in Fig. 10, that it closely parallels the bar 588 of the coin gauge device, and further, such that the exposed end of the gear lies relatively adjacent the bar. The bar and gear are operatively connected by a suitable, lost-motion type of connection, as at 633, the arrangement of the connection being such that longitudinal reciprocating movement of the bar 588, as effected by the coin-gauging and return movements of the gauge lever 584, will produce a corresponding rocking movement of the gear 630. The latter then, through the gear rack 70 75 629A, effects a corresponding reciprocating move-

lement of the control plate 623 relative to the coin-chute structure.

Before describing the operation of the sorting mechanism, it is to be noted that the control plate 623 is provided with a number of spaced, coin-stops 634, 635, 636 and 637, each comprising a U-shaped bar having its lower leg 638 secured to the plate, and its upper leg 639 free of the plate and spaced forwardly of one of the plate steps 624—627 sufficiently to provide clearance for the passage of a coin therebetween (Fig. 11). The legs of the stop 634 project laterally of the sorting structure 596, through apertures provided therein, in the zone between the coin-chutes 609 and 610 (Fig. 12), the arrangement of the stop being that the upper leg thereof normally projects laterally or across the passage 600. The other stops are similarly arranged, but located such that the stop 635 is between the chutes 610 and 611, the stop 636 between the chutes 611 and 612, and the stop 637 between the chutes 612 and 602. The function of these stops will appear now, in the following description of the operation of the sorting mechanism.

Assume for example, that a token is introduced to the singling zone of the machine, thus setting the machine in operation as before described. As the token is displaced toward and into the sorting mechanism, it actuates the gauge lever 584, and the latter in turn, and through the connection to the control plate 623, causes an initial movement of the plate toward the slot 621, but without entering one of its stepped elements therein. In this instance, the upper legs of the several coin stops 634—637 project across the passage 600. Further displacement of the token will carry it into the mouth 579, whence it drops downwardly, on edge, through the passage 598, through 597 and into the inclined passage 600. Entering the passage 600, the token will be effectively prevented from proceeding downwardly therein, by abutment with the upper leg of the coin stop 634. Hence the token will be constrained thereby, to drop into the token chute 609 and therefrom, into the token chamber 595E of the changer 595. Return movement of the gauge lever 584 to initial position, will thereby effect a retraction of the control plate 623 to its initial position.

In the instance of a dime passing through the machine, the control plate 623 will be similarly actuated, but the extent of forward displacement thereof in this case, is such as to project the step 624, over the token chute 609, and further such as to clear the upper leg of the coin stop 634 from the passage 600. Thus, the dime will then enter the passage 600, ride over the step 624 and enter the dime chute 610. Movement of the dime past the chute 610 is now prevented by the upper leg of the stop 635 spanning the passage 600. In a similar manner, successive displacements of the stepped control plate 623 and its several stops, in response to the passage of pennies, nickels and quarters through the singling and coin-gauge mechanism, will condition the sorting device for directing the coins into the proper coin chutes therefor. In the case of quarters, all of the coin stops 634—637 will be cleared from the passage 600, while the plate 623 effectively closes the coin chutes 609—612, so that the quarter may then gravitate through the length of the passage 600, into its chute 602 and thence into the chamber 595A of changer 595.

As shown by Figs. 11 and 12, provision is made for visual inspection of the coins passing downwardly in the several chutes 602 and 609—12, as

from the exterior of the fare box. For this purpose the forward housing wall 31 is recessed inwardly to the zone of the chute structure 596, as at 650, and in the lower forward wall section 651 of the chute structure 596, is located a window 652 giving a direct view of the several chutes and coins therein. To enable removal of spurious coins when thus visually detected in the chutes, the chute wall section 651 containing the window 652, is hinged at its lower end, as at 653, so that the operator may open the windowed section, through a handle 654, for direct access to the coins in the chutes. Necessarily, in this connection, means must be provided for retaining the coins in the chutes at least temporarily, and preferably long enough to facilitate visual inspection of the coins as well as coin removal when necessary. To this end, there is provided a coin-delay device which is operated in timed relation with the operation of the singling and sorting mechanism, through connection thereof with the drive shaft 569. The delay device includes, in the present example, a shiftable plate member 655 arranged horizontally along the lower end of the chute structure and operable in a slot 656 provided therein, such that the plate may be shifted or displaced forwardly in the slot to close the coin-discharge ends of the several chutes, as in the position thereof shown by Fig. 11. Actuation of the delay plate 655 from shaft 569 is presently effected by a yieldable connection comprising a rod 657 having one end 658 freely received in an aperture 659 provided therefor in an upstanding lug 660 on the rear end of the plate 655. The rod is yieldably connected to the lug through a coiled spring 661 bearing at one end against the lug and at its opposite end against a nut 662 on the rod. An adjustable assembly nut 663 threadedly received on the end 658 of the rod and abutting the lug 660, serves to retain the rod and spring in assembly with the lug. The opposite end 664 of rod 657 is longitudinally slidably journaled in an upstanding lug 665 on the shaft bracket 570, and carries a roller 666 serving as a cam-follower, in engagement with the cam face of a cam 667 secured to shaft 569. A return spring 668 connected between the plate 655 and a spring-bracket 669 serves to retract the plate from its chute-closing position, and also, to urge the cam-follower rod 657 toward the cam 667 such as to maintain the roller 666 in engagement with the camming surface thereof. The cam 667 is so formed and related to the follower rod 657, that the latter will be released once in each complete revolution of the cam, to permit retraction of the plate 655 from its chute-closing position, as effected by the return spring 668, for a predetermined short period sufficient to allow a coin to pass into the changer 595, the cam thereafter actuating the rod to return thereby the delay plate to its coin-stopping position. Further, the relative momentary retraction of the plate 655 is effected, through proper relation of the cam and follower actuation with the coin singling and sorting function of the mechanism, at a point in the operating cycle of the latter mechanism immediately preceding the delivery of a coin to one of the coin chutes. Thus a coin entering one of the chutes will be retained therein, as visible through the window 652, until immediately prior to the delivery of the next succeeding coin to the same or another of the chutes, and so on for all coins admitted to the machine. As will now readily appear, the function of the yieldable connection between the cam rod 657 and plate 655, including the spring

661, is such as to prevent stoppage of the shaft 569 in the event the plate 655 becomes jammed or is abnormally held in retracted position. The yieldable shaft drive connection to the plate also serves to permit manual retraction of the latter when desired, as accomplished by means now to be described.

As shown by Fig. 11, provision is made for stoppage of a coin in its chute by means operable independently of the delay-plate 655, and as controlled from the exterior of the fare box. A plate member 670 which may be somewhat similar to the plate 655, is arranged in the housing recess 650, oppositely to and in the plane of the plate 655. The plate 670 as manually controlled from the exterior of the machine, by a finger piece 671, is normally retracted from chute-closing position, to permit full operation of the automatically actuated delay-plate 655. However, when an operator desires to stop a coin in the chute structure, the control plate 670 may be then manually displaced inwardly against the plate 655, to retract the latter and to close the chutes independently thereof. Such retraction of plate 655 is readily permitted by the spring connection 661 and without affecting operation of the drive shaft 569, as pointed out hereinabove. Further, the manually controlled coin-stop plate 670 serves an additional purpose, in that it enables the operator to effect discharge of the last coin received in the chute structure immediately prior to or at the time the machine is cut out of operation, as at the end of the day or run. Such is effected by inward movement of plate 670 to retract the plate 655 from its chute closing position, whereupon a rapid retraction of plate 670 will open the chutes to allow the last coin to pass to its proper plate of deposit in the money changer. The discharge of the last coin occurs as above indicated, by reason of the fact that the plate 655 as displaced from chute-closing position by plate 670, will be momentarily retarded in its return movement under the influence of spring 661, by the counter-force of the spring 668, the delay thus effected being sufficient to permit full discharge of the coin.

The operation of the modified singling and sorting mechanism and the several provisions for coin-control in connection with the coin-receiving chute structure of the sorting mechanism, is believed to be now fully apparent from the foregoing description of parts and operation thereof, and hence, to require no further detailed description.

While the invention has been described by making specific reference to presently selected embodiments thereof, the detail of the description is to be understood solely in an illustrative and not in a limiting sense, since numerous variations are possible within the spirit of the intended scope of the claims hereunto appended.

I claim as my invention:

1. In a device for receiving and handling coins of different denomination, a coin-receiving receptacle, a coin-receiving and sorting mechanism spaced from said receptacle, a coin-engaging plunger cyclically operable through said receptacle for conveying coins therefrom to said sorting mechanism, a device for gauging the coins, operable by movement of a coin as effected by the plunger, said coin sorting mechanism being directly actuated by said coin gauge device, for sorting coins delivered thereto, plunger actuating means, first control means for said actuating means effective in response to the reception of a

coin in said receptacle and operable to initiate the operation of said actuating means, and second control means positioned by said plunger in its cyclic movement to maintain said first control means effective after the coin leaves the receptacle and until said plunger substantially completes its cyclic movement.

2. In a device for receiving and handling coins of different denomination, a coin-receiving receptacle, a coin storing device spaced from said receptacle, a coin-engaging plunger reciprocable from an initial position, through said receptacle for conveying a coin therefrom to said storing device, powered actuating means for said plunger, control means for said actuating means, arranged in said receptacle and effective in response to a coin in the receptacle, for initiating operation of said powered actuating means, and means on said plunger coacting with said control means during plunger reciprocation, for continuing operation of said actuating means until the return of the plunger to said initial position.

3. In a device for receiving and handling coins of different denomination, a coin-receiving receptacle, a coin receiving and sorting device spaced from said receptacle, a coin-engaging plunger reciprocable from an initial position, through said receptacle for conveying a coin therefrom to said sorting device, a device for gauging the coins, operable by movement of a coin as effected by said plunger, said coin sorting device being directly actuated by said coin gauge device, for sorting coins delivered thereto, powered actuating means for said plunger, control means for said actuating means, arranged in said receptacle and effective in response to the reception of a coin in the receptacle, for initiating operation of said powered actuating means, and means on said plunger coacting with said control means during plunger reciprocation, for continuing operation of said actuating means until the return of the plunger to said initial position.

4. In a device for receiving and sorting coins of different denomination, a coin receptacle, means providing a coin-discharge aperture spaced from said receptacle, a member operable for displacing coins from the receptacle to and into said discharge aperture, coin-singling means operatively associated with said receptacle and displacing member, effective to prevent displacement of more than one coin at a time by said member, a coin-gauge element positionable responsively to coin displacement from the receptacle and in accordance with coin-dimension, means providing a plurality of coin-passages near said discharge aperture, means under control of said coin-gauge element for establishing coin-delivery communication between the discharge aperture and said coin-passages selectively, as determined by coin-affected position of the gauge element, actuating means for said displacing member, first control means in said receptacle and responsive to a coin in said receptacle for initiating the movement of said actuating means, and second control means movable with said displacing member to maintain said first control means effective after the coin leaves the receptacle and until said displacing member returns substantially to initial position.

5. In a device for receiving and handling coins of different denominations, a coin receptacle, means for displacing coins singly from the receptacle, means providing a coin-aperture spaced from the receptacle and in the path of coin-displacement therefrom and adapted for the pas-

75

age of coins therethrough, means providing a downwardly inclined passage extending from the aperture, means providing a plurality of coin-chutes extending from the inclined passage and spaced in tandem along the passage, chute closure means slidably arranged relative to said chutes and selectively positionable to close one or more of the chutes, a coin-gauge extending into the path of coin-displacement from the receptacle and swingable by coin-abutment therewith to a position determined by at least one dimension of the coin, and means for translating swinging movement of said coin-gauge to sliding movement of said closure means for operating the closure means so as to position the latter selectively in accordance with the coin-positioning of said coin-gauge.

6. In a device for receiving and handling coins of different denominations, a coin receptacle, means for displacing coins singly from the receptacle, means providing a coin-aperture spaced from the receptacle and in the path of coin-displacement therefrom and adapted for the passage of coins therethrough, means providing a downwardly inclined passage extending from the aperture, means providing a plurality of coin-chutes extending from the inclined passage and spaced in tandem along the passage, chute closure means movably arranged relative to said chutes and selectively positionable to close one or more of the chutes, a coin-gauge extending into the path of coin-displacement from the receptacle and swingable by coin-abutment therewith to a position determined by at least one dimension of the coin, and means operatively connecting the coin-gauge to the closure means so that positioning of the closure means can be effected in response to movement of the coin-gauge in accordance with coin positioning of said coin-gauge.

7. In a device for receiving and handling coins of different denominations, a coin receptacle, means for displacing coins singly from the receptacle, means providing a coin-aperture spaced from the receptacle and in the path of coin-displacement therefrom and adapted for the passage of coins therethrough, means providing a plurality of coin-chutes arranged in tandem, means providing a passage for said coins extending from the coin-aperture and over the open ends of all of the coin-chutes, chute closure means movably arranged relative to said chutes, and selectively positionable to close one or more of the chutes so as to form a floor for said closed chute over which the coins may travel, a coin-gauge extending into the path of coin-displacement from the receptacle and swingable by coin-abutment therewith to a position determined by at least one dimension of the coin, and means for operatively connecting the coin-gauge to the closure means so that the position of the latter may be effected selectively in response to movement of the coin-gauge in accordance with coin-displacement of said coin-gauge.

8. In a device for receiving and handling coins of different denominations, a coin receptacle, means for displacing coins singly from the receptacle, means providing a coin-aperture spaced from the receptacle and in the path of coin-displacement therefrom and adapted for the passage of coins therethrough, means providing a downwardly inclined passage extending from the aperture, means providing a plurality of coin-chutes extending from the inclined passage and spaced in tandem along the passage, a chute closure member slidably arranged relative to said

chutes and positionable to close one or more of said chutes, and means including a gear and rack device, for translating swinging movement of said coin-gauge to sliding movement of said closure member to position the latter selectively, as determined by the coin-positioning of said coin-gauge for closing one or more of the chutes.

9. In a device for receiving and sorting coins of different denominations, a coin receptacle, means providing a coin-discharge aperture spaced from said receptacle, a member operable for displacing coins from the receptacle to and into said discharge aperture, coin-singling means operatively associated with said receptacle and displacing member, effective to prevent displacement of more than one coin at a time by said member, a coin-gauge element positionable responsively to coin-displacement from the receptacle and in accordance with coin-dimension, means providing a plurality of coin-passages near said discharge aperture, means under control of said coin-gauge element for establishing coin-delivery communication between the discharge aperture and said coin-passages selectively, as determined by coin-affected position of the gauge element, actuating means for said displacing member, and control means engageable first by coins received in the receptacle and secondly by the displacing member in its movement for initiating and continuing operation of said actuating means so long as a coin is present in said receptacle, the coins received in the receptacle being effective upon engagement with the control means for initiating operation of the actuating means and the displacing member being effective upon engagement with the control means for continuing operation of said actuating means until said displacing member has substantially completed a cycle and returned to its initial position, said control means being effective to cause cessation in the operation of said actuating means following displacement by said member of a last coin in the receptacle, and the return of said member substantially to its initial position.

10. In a device for receiving and sorting coins of different denominations, a coin receptacle, means providing a coin-discharge aperture spaced from said receptacle, a coin-displacing member cyclically movable from a retracted position to an advanced position and back again, coin-singling means operatively associated with said receptacle and displacing member, effective to prevent displacement of more than one coin at a time by said member, a coin-gauge element positionable responsively to coin-displacement from the receptacle and in accordance with coin-dimension, means providing a plurality of coin-passages near said discharge aperture, means under control of said coin-gauge element for establishing coin-delivery communication between the discharge aperture and said coin-passages selectively, as determined by coin-affected position of the gauge element, actuating means for said displacing member, and control means for the actuating means including contact members engageable by a coin in the receptacle when the coin-displacing member is retracted and by the displacing member when the latter is advanced, the operation of the actuating means being initiated by the coins and being continued by the coin-displacing member upon engagement of the contacts by the displacing member until the displacing member returns to its retracted position, the operation of the actuating means ceasing

when the displacing member is in its retracted position.

11. In a device for receiving and handling coins; a coin receiving receptacle; a coin storage receptacle; cycling means operable to move a coin from said receiving receptacle towards said storage receptacle; a first control for said means operable to initiate action of said means in response to the reception of a coin in said receiving receptacle; and a second control for said means, operable by said means in its movement to continue the activation of said means after displacement of the coin from said receiving receptacle and until said means has returned substantially to its initial position.

12. In a device for receiving and handling coins; a coin receiving receptacle having a support adapted to receive coins singly or in stacked relationship; a coin storage receptacle; a device for transferring a coin from the bottom of said receiving receptacle to said storage receptacle, said device being constructed and arranged to uncover said support in an initial position but to cover said support while transferring a coin therefrom; singling means adjacent said support to prevent the transfer of more than one coin at a time; actuating means for said device; control means engageable by a coin resting upon said support to initiate operation of said actuating means and subsequently engageable by said transfer device in its movement before and after complete disengagement by the transferred coin to continue operation of said actuating means until the coin has been completely transferred and said

support again uncovered by said transfer device.

13. In a device for handling coins, a coin supporting means adapted to support coins singly or in stacked relationship; a device for removing the bottommost coin from said support, said device being constructed and arranged to uncover said support in an initial position but to cover said support while removing a coin therefrom; singling means adjacent said support to prevent the removal of more than one coin from said support at a time; actuating means for said device; control means engageable by a coin resting upon said support to initiate operation of said actuating means and subsequently engageable by said device in its movement before and after complete disengagement by the removed coin to continue operation of said actuating means until the coin has been completely transferred and said support again uncovered by said

20 device.
